(57) **CLAIM**

The ornamental design for a digital sign, as shown and described.

DESCRIPTION

1. Digital sign

1.1 : Perspective

1.2 : Front

1.3 : Left

1.4 : Right

1.5 : Top

1.6 : Bottom

The broken lines depict portions of the digital sign that form no part of the claimed design; the waved lines on the top of reproductions 1.1 to 1.4 are to show that the length of lines has been omitted and form no part of the claimed design; reproduction 1.1 is a front perspective view of the digital sign; reproduction 1.2 is a front view thereof where the back view is a mirror image; reproduction 1.3 is a left view thereof; reproduction 1.4 is a right view thereof; reproduction 1.5 is a top view thereof; and reproduction 1.6 is a bottom view thereof.

1 Claim, 6 Drawing Sheets
